CLAIM

The ornamental design for a radial ultrasound needle biopsy device, as shown and described.

DESCRIPTION

FIG. 1 is a top, front, right side perspective view of a radial ultrasound needle biopsy device showing an embodiment of our new design in an un-activated configuration;

FIG. 2 is a top, front, right side perspective view of the radial ultrasound needle biopsy device of FIG. 1 in an activated configuration;

FIG. 3 is a right side elevational view of the radial ultrasound needle biopsy device of FIG. 1;

FIG. 4 is a left side elevational view of the radial ultrasound needle biopsy device of FIG. 1;

FIG. 5 is a back elevational view of the radial ultrasound needle biopsy device of FIG. 1;

FIG. 6 is a front elevational view of the radial ultrasound needle biopsy device of FIG. 1;

FIG. 7 is a top plan view of the radial ultrasound needle biopsy device of FIG. 1; and,

FIG. 8 is a bottom plan view of the radial ultrasound needle biopsy device of FIG. 1.

The dashed lines in the drawings are environmental and for illustrative purposes only and form no part of the claimed design. The dot-dash lines illustrate boundaries and form no part of the claimed design.
